UNITED STATES PATENT OFFICE.

CLAUDE M. WAGGONER, OF RIVERSIDE, CALIFORNIA, ASSIGNOR OF ONE-HALF TO
ISAAC B. POTTER, OF RIVERSIDE, CALIFORNIA.

STEPLADDER.

1,415,739.

Specification of Letters Patent.

Patented May 9, 1922.

Application filed May 16, 1921. Serial No. 489,855.

To all whom it may concern:

Be it known that I, CLAUDE M. WAGGONER, a citizen of the United States, and resident of city of Riverside, in the county of Riverside and State of California, have invented certain new and useful Improvements in Stepladders, of which the following is a specification, reference being had therein to the accompanying drawing.

10 The steps of step ladders are commonly subjected in use to strains in various directions by the weight of the users, such strains being transmitted to the stiles, of course.

It is highly desirable to combine lightness with entire rigidity at the junctions of the steps and stiles. Any relative movement of these parts causes constantly increasing looseness and leads to early ruin of the ladder.

20 In ladders of the type disclosed in my Patent No. 1,346,518, patented July 13, 1920, the strains mentioned are primarily borne by two bolts, which under pressure tend to compress the wood and thus permit the beginning of looseness.

The object of this invention is to avoid such compression of the wood and at the same time to increase very greatly the rigidity and strength of the structure without adding greatly to its weight or cost.

The new construction uses nearly the devices of said patent but holds each bolt at two widely separated points by brace members, preferably of sheet steel, which transmit thrusts by the step and particularly its marginal portions, in part at least, to a point upon the stile at a material distance below the end of the step.

In drawings,

40 Fig. 1 is a sectional view showing connected portions of a stile and step with parts broken away.

Fig. 2 is a section on the line 2—2, Fig. 1.

45 Fig. 3 is a section on the line 3—3, Fig. 1, parts materially beyond the plane of section being omitted.

Fig. 4 shows a tie bar for the headed ends of certain bolts.

In these figures, A represents a stile and B a step secured to the stile by two bolts C which pass horizontally through a tie-bar C', the stile and nuts D which are non-revolvable in recesses E in the lower side of the step and which align with holes F in which the bolts fit closely. The end of the

step is reinforced by a plate G having a perforated flange H bent upward against the terminal face and having at its opposite side two narrower flanges I which are perforated to receive the bolts and which lie in the recesses E between the nuts and the walls of the recesses. Were no other devices provided, strong thrusts by the steps would tend to compress the wood of the stile, causing looseness, and besides the structure would not have all desirable strength.

I add a metal plate J resting against the inner face of the stile at the end of the step and extending downward for a considerable distance. This plate is preferably V-shaped and has its narrow lower portion perforated to receive a bolt K which clamps it to the stile. A second analogous inclined brace plate L is provided and this has at its upper end wings M which extend into the recesses E and are perforated to receive the bolts C. This plate is narrowed like the other and its lower end is also secured by the bolt K, which is approximately in the middle of the stile. The marginal portions of the plate L are bent inwardly at right angles to form flanges L' which in the embodiment chosen for illustration, extend to and abut the stile A. The marginal portions of the plate J are shown as also bent inwardly and forming flanges J' which overlap and fit closely between the flanges L' the pairs of flanges thus affording each other mutual lateral support. Further, each plate having its flanges perpendicular to its body, lateral deflection of either plate is practically impossible, and of course the broad plates themselves can hardly yield edgewise. Obviously, flanging both plates is not indispensable.

Either of the two plates may be omitted without losing all the advantages of the other, and when both are used it is matter of expediency in manufacture whether they be integral, as it is also whether one or both be plane.

What I claim is:

1. The combination with a stile and a step, a broad metal plate extending into a recess in the lower side of the step at some distance from the stile, passing obliquely downward to the stile and having its lower end fixed to the latter at some distance below the step, and bolts passing through the stile, the upper portion of said plate, and the intervening portion of the step.

110

2. The combination with a step, of a wood stile having a long facing plate of metal, adapted to receive near its upper end the end of the step, a broad brace plate extending into the lower side of the step and passing obliquely downward to meet the facing plate materially below the step and having stiffening marginal flanges, bolts passing through the stile, the upper portion of each plate and the intervening portion of the step, and a bolt binding the lower parts of both plates to the stile.

3. The combination with a stile, of a step abutting the stile having a metal faced end and in its lower side recesses near the margins, respectively, of the step, a stile-facing plate interposed between said end and stile and extending downward to a material distance from the step, a broad brace plate provided with flanges lying in said recesses, respectively, and itself extending obliquely to the lower portion of the plate first mentioned, bolts passing through the stile, said plate and brace plate flanges and engaging nuts in said recesses, respectively, and a bolt binding the lower ends of said plate and brace plate to the stile.

4. The combination with a wood stile and a step abutting the same, of a plane metal brace sheet extending obliquely from the step to the stile, secured to both, and having

a flange fitting the angle between the two and perpendicular to the plane of said sheet.

5. The combination with a stile, an abutting step, and bolts binding the margins of the stile to the corresponding margins of the step, a metal plate interposed between the stile and step end and forming below the step a triangular body converging to the middle portion of the stile, a similarly converging brace sheet extending obliquely from the step to the lower portion of said body and having marginal flanges extending to said body, and means for securing the lower ends of said body and brace sheet to the stile.

6. The combination with a step having an end facing of metal, of a stile, a metal plate, between said facing and stile, extending downward along the stile and having marginal flanges projecting inwardly therefrom, a metal brace - sheet extending obliquely downward from the step to the stile and having lateral flanges fitting the angle made by the step and stile and overlapping the flanges first mentioned, bolts binding together the step end, stile, and interposed end facing plate, and means for rigidly fixing the lower end of the plate and sheet to the stile.

In testimony whereof I hereunto affix my signature.

CLAUDE M. WAGGONER.
